UNITED STATES PATENT OFFICE.

WILLIAM HILL, OF MOUNT PLEASANT, MICHIGAN.

DIRIGIBLE HEADLIGHT.

Application filed December 5, 1927. Serial No. 237,616.

This invention relates to a dirigible headlight for motor vehicles and is concerned with a mounting for headlights whereby the same may be swung in a horizontal plane about vertical axes independently of each other, and may also be tilted about a horizontal axis together so as to change the point where the light strikes the road in front of the motor vehicle; together with mechanism for manually operating the lights for such swinging and tilting movements. The invention consists in many novel details of construction and arrangement of parts for producing a practical and relatively simple construction of the character set forth.

An understanding of the invention may be had from the following description taken in connection with the accompanying drawing, in which,

Fig. 1 is a front elevation, partly in section, illustrating the mounting of the headlights between the front fenders of a motor vehicle.

Fig. 2 is an enlarged longitudinal vertical section through the mounting used for the headlights.

Fig. 3 is a fragmentary, vertical, longitudinal section through the front part of the motor vehicle illustrating the manually operated means for controlling the movements of said headlights, and

Fig. 4 is a detail in side elevation and vertical section showing the manually operated lever for tilting the headlights about a horizontal axis.

Like reference characters refer to like parts in the different figures of the drawing.

The headlights are mounted on and between the fenders 1 of the motor vehicle. A bracket 2 is permanently secured at the inner side of each fender from each of which a threaded stud 3 projects inwardly, the two studs being in horizontal axial alinement.

A hollow vertical sleeve 4 is attached at one side to each of the brackets 2, the studs 3 passing through the sleeves 4 and receiving nuts at their inner ends as shown in Fig. 2. A shaft 5 is rotatably mounted and positioned vertically in each sleeve 4 to the upper end of which the headlight 6 is secured. Each shaft 5 within its sleeve 4 is equipped with a beveled pinion 7.

At the side of each sleeve 4 opposite where it is attached to its bracket 2, a sleeve member 8 is permanently secured, said two members 8 extending toward each other and being located in horizontal alinement. Tubes 9

and 9^a, the former being longer than the latter, are connected to the sleeve members 8 and extend toward each other and at their inner ends are received with projecting sleeves 10^a at opposite ends of a gear box 10. The inner ends of the tubes 9 and 9^a are pinned and thus have permanent connection to said box 10 as shown.

Shafts 11 and 11^a lie lengthwise of and within the tubes 9 and 9^a and extend at their outer ends into the two vertical sleeves 4 and at their inner ends into the gear box 10. Each shaft 11 and 11^a at its outer end is equipped with a beveled pinion 12 which is in mesh with the adjacent pinion 7 on the vertical shaft 5. Each shaft 11 and 11^a at its inner end is equipped with a beveled pinion 13. The two pinions 13 mesh with similar beveled pinions 14 located within the gear box 10 secured to short shafts 14 which extend through the rear side of said box and are connected to operating shafts 16 by means of universal joint connections 17. The shafts 16 at their upper ends, after passing into the front driving compartment of the vehicle, are connected to operating members 18 by similar universal joint connections 17. The manually engageable member 18 for operating each shaft 16 lies directly back of the instrument board of the motor vehicle.

Two ears 19 extend downwardly from the lower side of the box 10 and a rod 20 lies between said ears being pivotally connected thereto, and extends upwardly and to the rear into the front driving compartment of the vehicle and through the instrument board as shown in Figs. 3 and 4. An operating member 20, eccentrically mounted and having a handle 21^a for turning it about its pivotal mounting, is provided with an arc-shaped slot 22 through which the rear end of the rod 20 is placed. The slot 22 is eccentric with respect to the pivotal axis about which the member 21 turns so that on pushing downward on the handle 21^a, rod 20 is drawn longitudinally to the rear thereby tilting the box 10, tubes 9, sleeves 4 and the headlights 6 at the upper end of said sleeves so as to project light from the lights on to the road nearer the front end of the vehicle. And when the handle 21 is operated in the opposite direction the light is projected on to the road farther away from the vehicle.

It is evident that either headlight 6 may be turned about the axis of the shaft 5 on which it is mounted independent of the other,

there being two of the operating rods 16, one for each headlight. It is also evident that by operating the member 21 both headlights may be tilted about the horizontal axis of the shafts 11 and 11^a. This construction permits the control of the lights for practically all driving purposes. On meeting a vehicle the lights may be turned downwardly. On turning a corner the light on the near side may be swung so as to follow the inner turn of the corner while the other may remain in its direct ahead position; or many other positions of either of the lights can be secured by proper operation of the shafts 16 which individually control the two lights.

The invention is defined in the appended claims and is to be considered comprehensive of all forms of structure coming within their scope.

20 I claim:

1. In a construction of the class described, two spaced apart supports, a vertical sleeve secured to each support and pivoted on a horizontal axis, a vertical shaft rotatably mounted in each sleeve, a headlight carried at the upper end of each shaft, a pinion on each shaft, a hollow box located between said sleeves, tubes rigidly connecting opposite ends of the box with said sleeves, shafts extending through said tubes at the outer ends being equipped with pinions engaging with the pinions on said vertical shafts, other pinions on the end of said second mentioned shaft within said box, additional pinions meshing with said last mentioned pinions, means for manually turning either of said

additional pinions to thereby selectively turn either headlight about the vertical axis of the vertical shaft on which it is carried and means for rotating said hollow box, tubes and sleeves on a horizontal axis.

2. In a construction of the class described, two front spaced apart fenders of a vehicle, a support attached to the inner side of each fender, a pair of spaced apart headlights mounted on and carried by said supports to tilt about a horizontal axis, means for mounting said headlights to turn about separate vertical axes, means for tilting both headlights simultaneously about said horizontal axis, and means for selectively and individually turning either headlight about its vertical axis of rotation.

3. In a construction of the class described, two spaced apart brackets, a horizontal tubular member extending between said brackets and rigidly fixed thereto, means for mounting said brackets and tubular member to rotate on the axis of the tubular member, a vertical shaft in each bracket mounted for rotation on a vertical axis, a housing interposed in said tubular member between its ends and rigidly attached thereto, means connected with said housing for rotating the same and its attached tubular member and brackets on a horizontal axis, means located within said housing and extending through said tubular member for rotating both of said vertical shafts, said means extending outside of said housing for manual actuation.

In testimony whereof I affix my signature.

WILLIAM HILL.
